UNITED STATES PATENT OFFICE

2,642,288

EXERCISE MACHINE

Joseph D. Bell, San Francisco, Calif.; Pearl B. Bell, administratrix of said Joseph D. Bell, deceased.

Application August 1, 1949, Serial No. 107,873

3 Claims (Cl. 272—79)

1

The present invention relates to improvements in exercising machines and contemplates certain further developments in connection with the exercising machine described and claimed in my Patent Number 2,455,548 of December 7, 1948.

The patented machine consisted in its principal features of a base, a post rising from the front section thereof; an inclined track disposed over the rear section, a handle bar at the upper end of the post, a pair of foot pedals swingable with respect to the post, a seat; a brace supporting the seat and movable over the inclined track, and a link connection between the foot pedals and the brace whereby a seat occupant by operation of the foot pedals could swing the lower end of the brace back and forth for raising and lowering the seat, while grasping the handle with his hands.

In this device the handle bar was stationary so that the upper portion of the body of a seat occupant grasping the handle bar and operating the foot pedals would remain relatively unaffected except for the up and down movement of the seat.

In the present invention it is proposed to arrange the handle bar swingable with respect to the supporting post and to provide for a connection between the handle bar and the foot pedals operative to cause the handle bar to swing backwards when the foot pedals are moved forward and vice versa to cause the foot pedals to move backward upon a forward movement of the handle bar, the general object of this arrangement being that operation of one of the members automatically operates the other one.

It is further proposed in the present invention to use the connection between the foot pedals and the handle bar also as a driving connection for the brace supporting the seat so that a seat occupant pushing on the pedals and pulling on the handle bar will raise the seat while the weight of the seat occupant will automatically return the foot pedals and the handle bar to their original position.

One of the principal objects of the present invention as compared with the patented one is that the upper part of the body of the seat occupant partakes of the exercising motion as much as the legs and that on the forward movement of the feet the body swings backwards while the seat is raised so as to cause the entire body to straighten out into substantially horizontal position toward the end of said movement.

Further objects and advantages of my invention will appear as the specification proceeds,

and the novel features of my invention will be fully defined in the claims attached hereto.

The preferred form of my invention is illus-

trated in the accompanying drawing, in which

5 Figure 1 shows a perspective view of my exer-

cising machine, and

Figure 2, a detail view of a handle bar attach-

ment used in the machine.

While I have shown only the preferred form of

10 my invention, I wish to have it understood that

various changes and modifications may be made

within the scope of the claims attached hereto

without departing from the spirit of the inven-

tion.

15 Referring to the drawing in detail, my exer-

cising machine comprises in its principal features

a main frame 1 having a pair of posts 2 at the

front end thereof and an inclined track 3 mount-

ed over the rear section, a frame 4 swingable in

20 the front portion of the main frame as at 5 and

having a seat 6 mounted upon its rear end over

the inclined track 3; a brace 7 pivoted to the

frame 4 as at 8 and carrying at its lower end a

roller 9 adapted for back and forth movement

25 on the inclined track 3. A pair of foot pedals 10

are mounted on a frame 11 swingable in a for-

ward extension of the posts shown at 12, a han-

30 dle post 13 is pivoted in the frame posts as at 14,

and a link 15 connects the foot pedal frame, the

brace 7, and the handle post 13, whereby upon a

35 forward movement of the foot pedals the brace

is moved toward vertical position for raising the

seat while at the same time the handle bar 16 at

the upper end of the post 13 is swung rearwardly.

40 The frame 1 is preferably made in the form of

a pipe of substantial diameter, the pipe being

bent intermediate its length to provide a raised

45 front section 17 and being held against tilting by

a cross-bar 18 at the rear end and the spacing

between the posts at the front end. It may fur-

ther be braced by suitable diagonal members 19.

The inclined track 3 is supported over the

rear portion of the main frame 1 by means of

45 brackets 20 and 21, one of which may be made

adjustable by a hook member 22 engaging in any

one of several notches 23.

The track 3 is here shown as having a substan-

50 tially horizontal rear portion, an inclined inter-

mediate portion and a somewhat steeper front

portion, but it is apparent that the shape of the

track may be changed in many different ways

for producing desired effects upon the body of

the person using the machine.

The frame 4 may be made substantially v-

55 shaped so as to cause its lower portion to strad-

die the posts. It may be formed, intermediate its length, with a stop 24 adapted to bear on the brace 7 to prevent the latter from going beyond vertical position.

The posts 2 are held in spaced and parallel relation by suitable spacing members 25, and the upper portions of the posts are telescoped into the lower portions as at 26 so as to allow the upper portions to be pulled out whenever it is desired to reduce the overall dimensions of the exercising machine when not in use.

The foot pedal frame 11 is swingably supported in the post extensions 12 as shown at 27.

The handle post 13 is also made in two telescoping sections as indicated at 28 so as to allow the upper section to be pulled out of the lower section along with the removal of the upper portions of the posts from their lower portions. The lower section 30 of the handle post is pivoted to a pin 31 which latter is welded or otherwise permanently secured to the connecting link 15. The telescoping connection in the handle post also makes the latter extensible to follow the movements of the connecting link 15.

In operation, a seat occupant will place his feet on the pedals 10 while grasping the handle bar 16 with his hands. He may simultaneously push forward on the pedals and pull backward on the handle bar so as to straighten out his entire body while at the same time the seat is moved upwards to raise the middle portion of the body. At the end of the movement the body will be fully extended in slightly inclined or almost horizontal position. When the efforts on the foot pedals and the handle bar are relaxed, the weight of the body of the seat occupant will automatically return the different parts to their original positions due to the effect of the inclined track.

I claim:

1. An exercising machine comprising a main frame having a post rising therefrom, a seat supported by the main frame rearwardly of the

post, an actuating member for the seat, a foot support member swingably supported by the post and located for operation by a foot of a seat occupant, a pump handle member pivoted in the post rearwardly of the foot support member and located for operation by a hand of the seat occupant, and a link connecting the three members.

2. An exercising machine comprising a frame, 10 a handle supporting member pivoted to the frame, a pedal supporting member pivoted to the frame forwardly of the handle supporting member, a seat operating member having a free end movable with respect to the frame, and a common link connecting the three members for moving the latter in unison when one of them is actuated.

3. An exercising machine comprising a frame having a post rising from the front end thereof, 20 a handle supporting member, a pedal supporting member, a seat supporting member, means for pivotally connecting the three members to the post at spaced points, a seat operating member, and a single link connecting the seat operating member and the first two members for causing the same to move in unison when one of them is actuated.

JOSEPH D. BELL.
